RAILWAY TRAFFIC CONTROLLING APPARATUS

Leslie Hurst Peter and Douglas Goldie Shipp, King's Cross, London, England, assignors, by mesne assignments, to The Union Switch and Signal Company, Swissvale, Pa., a corporation of Pennsylvania

Application March 9, 1940, Serial No. 323,196
In Great Britain March 10, 1939

15 Claims. (Cl. 246—3)

This invention relates to railway traffic controlling apparatus of the kind in which the selective operation of a number of traffic controlling devices such as railway points and signals is arranged to be electrically effected from a point of control by means of code currents transmitted through line wires connecting the point of control and the devices to be controlled. The latter are usually divided into groups corresponding to local regions of control, termed field stations, and the apparatus enables any desired field station and any desired device at that station to be selectively operated, arrangements being usually provided for indicating at the point of control, also by means of codes transmitted through the line wires, the setting or operation of the devices at the field stations and other information such as the occupancy of track sections by trains or vehicles.

Centralised traffic control systems of this character are now well known, and the present invention has for its object to provide certain improvements therein which are however not limited to any particular code system.

It is in some cases desirable that a group of devices normally constituting a field station and arranged for centralised control in the manner above described, should be also arranged for local control from a subordinate point of control located adjacent to the station, it being understood that the centralised and local controls are alternative to one another. The present invention provides arrangements for this purpose whereby the transfer from centralised to local control conditions is effected in a simple, safe and reliable manner.

According to the principal feature of the invention, the transfer from centralised to local control is effected by the transmission of a special control code signal for this purpose from the central point, the reception of this code signal at the field station being arranged to render operative at the station suitable arrangements which permit local control levers, switches or their equivalent to effect the operation of one or more of the track switches, signals, or other traffic controlling devices, at the field station, these arrangements when thus rendered operative cutting off or otherwise superseding the normal apparatus for the remote control, from the central point, of the devices involved.

The arrangements above referred to are preferably only rendered operative to permit the establishment of the local control provided that the traffic controlling devices involved are in

their normal positions or settings, the establishment of the local control when thus permitted being actually effected by the local operator setting a king lever or switch which effects directly or through suitable relays the disconnection of the transmission line, the operating circuits or relays of the devices to be controlled being transferred to the local control levers or switches by the action of relays controlled by the special control code signal above referred to.

This special code signal may be arranged to energise a suitable relay at the field station receiving apparatus, for example, the relay 7XS or 7YS normally provided for signal control in the centralised traffic control system of the Westinghouse Brake & Signal Company's British Patent No. 399,539, dated April 4, 1932, which corresponds with the United States application, Serial No. 538,380, filed May 18, 1931, by C. S. Snavely et al. for Remote control systems. It is to be understood that the relay selected for this purpose is a relay not required for the control of a signal at the station in question.

The invention is illustrated by way of example in the accompanying drawings as applied to a centralised traffic control system of the general character described in the British Patent No. 399,539.

Figure 1 of the drawings is a diagram of a simple form of field station to which the invention may be applied. Figures 2 and 3 are diagrams of connections of portions of two of the storage units at the field station adapted for the control of the traffic governing apparatus at the field station in accordance with one form of the invention. Another form of the invention is illustrated in Figures 4, 5, 6 and 7 of which,

Figure 4 is a view similar to Figure 1 of a field station comprising shunt signals in addition to main signals. Figures 5 and 6 are views similar to Figures 2 and 3 of portions of two field storage units at the field station and Figure 7 is a diagram of connections of a local control panel cooperating with these storage units, for the control of the shunt signals.

Referring now first to Figures 1, 2 and 3 it will be seen that the field station is located at a portion of the track comprising a main line having track sections DT, ET, FT, and a loop line having a track section CT and leading to or from the main line through a track switch operated by an electrically actuated point machine W in the usual manner.

Signals RA, RB are provided for controlling traffic from left to right along the main and loop

lines respectively, together with signals LA, LB for the control of traffic along these lines in the opposite direction.

The relay and other apparatus required for the code control of the track switch and signals at the field station from a remote point of control are located in a cabin CB which also contains the apparatus for local control of the switch and signals.

The code control apparatus in the cabin comprises the field station equipment described in the British Patent No. 399,539, including two field storage units FSU1 and FSU2 each similar to the unit illustrated in Figure 10 of this patent. The portions of the units FSU1 and FSU2 with which the present invention is concerned are illustrated in Figures 2 and 3 respectively and the operation of the various relay elements of these storage units is fully described in the British Patent No. 399,539.

As therein explained a control code consisting of X, Y and Z code elements is transmitted from the remote point of control to the field station to effect the operation of the relays 6XS and 6YS of storage unit FSU1 to control the point relay WR controlling the operation of the switch machine W and to also effect the operation of the relays 7XS, 7YS of this storage unit to control the signal relays LHS and RHS. These relays 6XS, 6YS, 7XS and 7YS are energized through circuits controlled by delivery relay D from conductors 26, 27, 28, 29 leading from the field coding unit.

An interlocked change-over relay, QR (see Figure 3) is provided which is adapted to be set into its normal position or into its reverse position according to whether its energising coil N or its energising coil R is energised. Relay QR may, for example, be of the type shown in Letters Patent of the United States No. 2,164,823, granted July 4, 1939, to Kershaw et al.

The relay QR when set into its normal position closes a number of contacts QR(N) interposed in various circuits of the apparatus as shown in Figures 2 and 3, and amongst others the circuits leading from the conductors 56, 57 of the storage unit FSU1 to the point relay WR and the circuits leading from the wires 58, 59 of the unit FSU1 to the signal relays LHS and RHS. Furthermore, when the relay QR is in its normal position the circuits of the wires 26, 27, 28, 29 leading from the field coding unit to the contacts of the delivery relay D are also completed through contacts of the relay QR indicated at QR(N).

A point control lever P having contacts P(N), P(R) closed respectively when the lever is in its normal and reverse positions is provided at the field station for effecting local control of the point relay WR, a signal control lever S being similarly provided adapted normally to occupy a central position in which a contact S(N) is closed and to be set to a right or left position in which a contact SR(R) or SL(R) is closed to energise the signal relay LHS or RHS so as to clear the signals RA and RB or LA and LB, it being understood that the selection of the signal RA or RB and LA or LB is effected automatically in accordance with the position of the track switch in a well known manner.

The setting of the relay QR to its normal or reverse position is arranged to be controlled by change-over control relays, XQR, YQR one or the other of which is energised according to whether the relay 7YS in the second field storage unit FSU2 is de-energised or energised. It

will be understood that this relay 7YS is the relay allotted to the special code signal for the transfer from central to local control.

A hand operated king lever K is provided at the field station having an electrically released lock KL adapted to retain the lever K in its normal position (for local control) or in its reverse position (for central control) when moved there-to.

10 The king lever K is arranged, when in its reverse position, to lock mechanically or otherwise the local control point and signal levers P, S so that these cannot be operated. The king lever K when in its reverse position is also arranged 15 to complete through contacts K(R) the circuits of conductors 28, 29 leading to the delivery relay D of the field storage unit FSU2 so as to permit this unit to transmit the special code signal to the appropriate relay 7YS in this unit.

20 The operation of the apparatus is as follows:

Under central control conditions, the king lever K being in its reverse position the control of the point relay WR is effected by the relays 6YS and 6XS of the field storage unit FSU1 in the manner described in the prior patent since the conductors 56, 57 leading from the contacts of these relays are connected to the point relay WR through the closed contacts QR(N) of the change-over relay QR. The relay QR is maintained in its normal setting when the king lever K is in its reverse position in the following manner.

25 Relay 7YS of storage unit FSU2 is normally de-energised while relay 7XS of this unit is normally maintained energised through a local stick circuit from terminal B, conductor 46, front contact B2 of relay 7XS, contact D1 of relay D, back contact C4 of relay 7YS and the energising coil of this relay to terminal C. An energising circuit for relay XQR is completed from terminal B, conductor 55, back contact A5 of relay 7YS, front contact A5 of relay 7XS, conductor 58 a back contact YQR2 of relay YQR, the energising coil of relay XQR to terminal C.

30 Relay XQR being thus energized a circuit is completed from terminal B through front contact XQR1 of relay XQR and coil QRN of change-over relay QR, to terminal C. This circuit also includes the contacts of the switch indication relay KR and of the signal relays LH and RH shown in Fig. 11 of the prior patent so as to ensure the usual safety conditions.

35 The relay QR being thus set into its normal position the control of the point relay WR and the signal relays LHS and RHS can be effected through the storage unit FSU1 by remote code control in the manner described in the British Patent No. 399,539 since the circuits of the conductors involved, viz., 56, 57, 58, 59, and 29, 28, 27, 26 are all completed at the contacts QR(N) of the relay QR.

40 Under these conditions the king lever K is held locked in its reverse position owing to the energising circuit of the lock KL being interrupted at the contact QR(R) of the relay QR.

45 When it is desired to establish local control at the field station, a special code signal is transmitted from the central point to the station and since the contacts K(R) of the king lever K are closed, current is transmitted from the field coding unit through conductor 29 and the delivery relay D of storage unit FSU2 to energise relay 7YS of this storage unit, relay 7XS having been deenergised by the interruption of its stick circuit at the contacts of the delivery relay D. Re-

lay 7YS having been thus energised and relay 7XS deenergised, a stick circuit for relay 7YS is completed through conductor 46 as will be evident from Figure 3. The deenergisation of relay 7XS will interrupt the circuit of relay XQR at front contact A5 of relay 7XS and (relay 7YS being energised) will complete an energising circuit for relay YQR from terminal B, conductor 55, front contact A5 of relay 7YS, back contact B4 of relay 7XS, conductor 59, back contact XQR2 of relay XQR, and coil of relay YQR to terminal C.

Relay XQR being thus deenergised and relay YQR energised a circuit is completed from terminal B contacts of the track switch and signal indication relays above referred to (thereby ensuring that the track switch and signals are in their normal positions), front contact YQR1 of relay YQR, coil R of relay QR to terminal C. The circuit of coil N of relay QR is interrupted at the contact XQR1 of relay XQR and the energising circuit of the lock KL is completed at contacts YQR1 and QR(R). Accordingly when the local operator moves the king lever K from its reverse position towards its normal position so as to close a contact AE (this contact being closed during the intermediate range of movement of lever K from one position to another), the lock KL is operated and the lever K is free to be fully moved to its normal position.

Until however, the lever K is actually moved from its reverse position the operator at the central point can evidently cancel the operations effected by the special code signal, since the circuits of the conductors 28, 29 at the storage unit FSU2 are still completed at the contacts K(R) and the storage unit FSU2 is consequently still in communication with the central point of control.

The setting of the relay QR from its normal position will, however, interrupt the circuits of the conductors 26, 27, 28, 29 at the contacts QR(N) of field storage unit FSU1, so that control of the points and signals from the central point is no longer possible.

As soon, however, as the local operator has moved the king lever K from its reverse position the circuits of the conductor 28, 29 of storage unit FSU2 will be interrupted at the contacts K(R) so that code control from the central point is cut off.

The movement of the king lever K to its normal position is arranged to complete a second holding circuit for relay 7YS of the storage unit FSU2 extending from terminal B over the lever contact K(N) and conductor 47, so that this relay and consequently relay YQR will be held energised as long as lever K remains in its normal position irrespective of any operation of the delivery relay D. The opening of the contacts QR(N) and the closing of the contacts QR(R) of the storage unit FSU1 is effective to release the local point and signal levers P and S for operation and by setting the point lever P to its normal or reverse position the relay WR is correspondingly energised through circuits including contacts QR(R) of relay QR and contacts P(N) or P(R) of lever P and also the contacts of the usual approach locking and track relays LMR, RMR and ETR which as here shown are arranged as shown in Figs. 8 and 9 of the British Patent No. 415,737, dated March 3, 1933, and therefore need not be described in detail.

Similarly the signals may be locally controlled

by the signal lever S which effects the energisation of the signal relays LHS or RHS through circuits including the contacts SL(R) and SR(R) of lever S, contacts QR(R) of relay QR and interlocking contacts RHS1 and LHS1 of the relays RHS and LHS.

It will be noted that the local energising circuits for both the relays LHS and RHS include a front contact GSR1 of a stick relay GSR, the relay GSR being energised when the lever S is at normal and maintained energised until a train or vehicle enter track section E and deenergises the corresponding track relay so as to interrupt the stick circuit of relay GSR at track relay contact ETR1.

As shown in Figure 3, an indication lamp KLL is provided the circuit of which is completed when relay YQR is energised (so as to close front contact YQR1) and contact QR(R) of relay QR is closed. The lamp KLL will thus indicate to the local operator when the king lever K is free to be operated as above described.

The operations of the change-over relay QR and of the king lever K are indicated at the central point of control by the transmission of indication codes each of which includes an impulse having an X, Y or Z characteristic controlled through the conductor 35 of storage unit FSU2. These indication codes are transmitted

as follows: As soon as the change-over relay QR has been set to its reverse position so as to release the lock KL of the king lever K, a starting circuit is closed in Fig. 3 from terminal B over contacts K(R) and QR(R) to conductor 54 which, as shown in Fig. 10 of British Patent No. 399,539, includes a back contact C3 of a valve relay 7V. The closing of this circuit initiates the transmission of a code in which the impulse controlled over conductor 35 has a Z characteristic. At the end of this code relay 7V picks up to open the circuit over conductor 54 and to prepare an alternative starting circuit over conductor 48. When the lever K has been moved to its normal position for establishing local control the alternative starting circuit is completed by a connection from terminal B over contacts QR(R) and K(N) to conductor 48. This initiates a code in which the impulse controlled over conductor 35 has a Y characteristic, whereupon the valve relay 7V is released to open the circuit including conductor 48 and to again prepare the one including conductor 54.

When it is desired to re-establish central control, the action is initiated by the local operator, who after setting the track switch and the signals to normal, will move the king lever K to its reverse position, the lock KL on this lever being, however, still releasable, since relay QR is in its reverse position. The setting of the king lever K to reverse will complete the circuits of the conductors 28, 29 of the storage unit FSU2 at lever contacts K(R) and will again complete the starting circuit which includes conductor 54, to initiate a code to cause a Z code impulse to be transmitted to the central point of control through lever contact K(R), relay contact QR(R) and conductor 35 of storage unit FSU2. The operator at the central point being thus notified that local control is to be terminated, will transmit a special code signal to cause the energisation of the relay 7XS and the release of relay 7YS of the storage unit FSU2 so as to energize relay XQR and release relay YQR and thereby restore the change-over relay QR to normal. The control circuits of the relays WR,

RHS and LHS will thereby be reconnected to the corresponding conductors of the storage unit FSU1. The setting of the relay QR to normal will also prevent the release of the lock KL on the king lever K so that the latter is held locked in its reverse position. In these settings of the king lever K and relay QR the starting circuit prepared as the result of the transmission of the last code, which extends to terminal B over contacts K(R) and QR(N) to conductor 48 is closed to initiate a code in which an X indication code impulse is transmitted to the central point of control, through conductor 35 of storage unit FSU2, thereby notifying that the transfer to central control has been completed.

The apparatus at the field station is provided with arrangements for effecting release of the approach locking of the track switch after an interval of time in the well known manner, this being effected by the action of a relay JR when control from the central point is established.

When on the other hand, local control is established, the release of the approach locking is arranged to be effected by a slow-acting relay JRS controlled by means of a push-button switch JRB, the relay JRS controlling the action of the relay JR.

The occupancy of the track circuits ET, FT, and the setting of the track switch and signals by code control from the central point are arranged to be indicated by codes transmitted from the field station in which the character of the indication impulses is governed by the relay contact mechanism indicated at M in Figure 2, in a manner which will be evident without detailed illustration or description, further than to point out that the designations of these contacts are those of the relays which operate them. Relays ETR and FTR are the track relays for sections ET and FT; relay KR is the usual polar neutral indication relay for the track switch of Fig. 1, and relays LGP and RGP are indication relays controlled by the signals like the similarly designated relays in British Patent No. 415,787.

Referring now to the modified apparatus shown in Figures 4, 5, 6 and 7, it will be seen that the main signals RA, RB and LA, LB controlled by relays LHS and RHS are arranged to be controlled from the central point only while shunt signals RAS, RBS and LS are arranged to be controlled locally from the field station only, the control of the track switch being effected either from the central point by code control or by the operator at the field station.

As shown in Figure 7, the local control apparatus at the field station comprises a control panel T on which are mounted a king switch KS, a point control switch TP and a shunt signal control switch TS. Two additional relays ZR(N) and ZR(R) are also provided at the field station for effecting the same interlocking and code lock-out features as the king lever K in the system previously described.

The relay ZR(N) is arranged to be energised when the king switch KS is in its normal position (for local control) through a circuit from terminal B, contacts KSN of switch KS, back contact ZR(R) 1 of relay ZR(R) and the coil of relay ZR(N) to terminal C. The relay ZR(R) is deenergized under these conditions since its circuit is interrupted at back contact ZR(N) 1 of relay ZR(N).

Relay ZR(R) being deenergized, the circuits of conductors 28, 29 at storage unit FSU2 of Fig-

ure 6 are interrupted at contacts ZR(R) 2 and ZR(R) 3 of this relay.

Relay YQR having been energized by central control and change-over relay QR having been thereby set to its reverse position as previously described with reference to the preceding figures, the point relay WR is connected to the contacts of the point control switch TP through conductors TP1 and TP2 and as will be apparent from Figures 5 and 7, under these conditions the point relay WR can be energized in the normal or reverse direction by correspondingly actuating the control device TP, through a circuit including the contacts QR(R) of relay QR, the conductors TP1, TP2, contacts ZR(N) 2 and ZR(N) 3 of relay ZR(N).

Similarly, by actuating the signal control device TS, operating current for the shunt signals RAS, RBS or LS is supplied thereto through a circuit including contact ZR(N) 4 of relay ZR(N), the appropriate contacts of the control device TS, contacts QR(R) of relay QR, contacts of the switch indication relay KR and the conductor RAS1, RBS1 or LS1.

When the king switch KS is set into its reverse position to restore central control, relay ZR(R) is energized through a circuit extending from terminal B over contacts of the switch and signal indication relays and of the levers TS and TP, all in their normal positions, contacts KSR of the king switch KS and back contact ZB(N) 1 of relay ZR(N) through relay ZR(R) to terminal C. The circuits of conductors 28, 29 of storage unit FSU2 of Figure 6 are thereby completed at contacts ZR(R) 3 and ZR(R) 2 so that the central control of the relays XQR and YQR is again established. Contact ZR(R) 6 completes a starting circuit over conductor 54, causing an indication code to be transmitted which includes a Z impulse controlled over conductor 35. The central office operator then sends a special code signal as hereinbefore described to effect the energisation of relay XQR and the release of relay YQR to thereby restore relay QR to normal. When relay QR assumes its normal position, the central control of the relays LHS and RHS is again established, central control of the point relay WR being also restored since the contacts QR(N) of relay QR are closed.

In other respects the operation of the systems is similar to that of the system previously described.

The local control panel T is provided with an indication lamp TL which is supplied with current when the contacts QR(R) of relay QR are closed so as to indicate that the panel is free for operation. Indication lamps TPN and TPR are also provided on the panel T and are controlled through the contacts of the indication relay KR for the track switch so as to indicate the setting of this switch under local control conditions.

It will be understood that the panel T may be provided with control devices similar to the device TS for the control of the signal relays RHS and LHS in addition to or as an alternative to the control device TS for the shunt signals.

It will be understood that in both systems the local control is entirely suspended so long as central control is in operation and can only be permitted to be established by action initiated from the central point and completed by the co-operation of the local operator. Furthermore, when local control has been established by the local operator, the central control is suspended and can only be restored by action initiated by

the local operator and completed by the cooperation of the operator at the central point.

The invention is evidently not limited to the particular arrangements above described and illustrated by way of example which may be modified in various respects without exceeding the scope of the invention.

Having now described our invention, what we claim is:

1. In a railway traffic controlling system, impulse signaling apparatus for communicating between a central point of control and a field station, a plurality of railway traffic governing devices at said station, and a dual system of control for said devices comprising control relays responsive to impulse signals transmitted at times from the central point of control for controlling the operation of said devices, manually operable control levers at another point of control for at other times controlling such operation by the operation of said levers, and change-over means responsive to a special impulse signal transmitted from the central point of control for effecting the transfer from central control to the control of said devices by said levers.

2. In a railway traffic controlling system, impulse signaling apparatus for communicating between a central point of control and a field station, a plurality of railway traffic governing devices at said station, control relays responsive to impulse signals transmitted at times from the central point of control for controlling the operation of said devices, manually operable control levers at a local point of control for at other times controlling such operation by the operation of said levers, and change-over means responsive to a special impulse signal transmitted from the central point of control provided all of said devices are in their normal condition for effecting the transfer from central control to the local control or from local control to the central control.

3. In a railway traffic controlling system, impulse signaling apparatus for communicating between a central point of control and a field station, a plurality of railway traffic governing devices at said station, a change-over relay and a king lever at said station each having a normal and a reverse position, a plurality of control relays at said station responsive to impulse signals transmitted from said central point and effective only when said change-over relay is in its normal position to control said devices, a plurality of control levers at said station for controlling said devices locally, said levers being effective only when said change-over relay is in its reversed position, other control relays at said station responsive to special impulse signals transmitted from said central point for operating said change-over relay from normal to reverse or from reverse to normal when said king lever is reversed, and circuit means effective as long as said king lever is normal to prevent the operation of said change-over lever in response to said special impulse signals.

4. In a railway traffic controlling system, impulse signaling apparatus for communicating between a central point of control and a field station, a plurality of railway traffic governing devices and a change-over relay at said station, a plurality of control levers at said station for controlling said devices locally said devices being subject to control in accordance with the positions of said levers only when said change-over relay is in a reversed position, means for

controlling said devices in accordance with the character of different impulse signals transmitted from said central point effective only when said change-over relay is in a normal position, and means for controlling said change-over relay in accordance with the character of special impulse signals transmitted from said central point.

5. In a railway traffic controlling system, impulse signaling apparatus for communicating between a central point of control and a field station, a plurality of railway traffic governing devices and a change-over relay at said station, a plurality of control levers at said station for controlling said devices locally said devices being subject to control in accordance with the positions of said levers only when said change-over relay is in a reversed position, means for controlling said devices in accordance with the character of different impulse signals transmitted from said central point effective only when said change-over relay is in a normal position, a locally operable king lever at said station, and means effective only when said king lever is in its reversed position for controlling said change-over relay in accordance with the character of special impulse signals transmitted from said central point, and an indication lamp associated with said king lever for indicating the position of said change-over relay.

6. In a railway traffic controlling system, impulse signaling apparatus for communicating between a central point of control and a field station, a plurality of railway traffic governing devices and a change-over relay at said station, a plurality of control levers at said station for controlling said devices locally said devices being subject to control in accordance with the positions of said levers only when said change-over relay is in a reversed position, means for controlling said devices in accordance with the character of different impulse signals transmitted from said central point effective only when said change-over relay is in a normal position, a locally operable king lever at said station, means effective only when said king lever is reversed for controlling said change-over relay in accordance with the character of special impulse signals transmitted from said central point, locking means for preventing operation of said king lever, and means effective only when said change-over relay is reversed for energizing said locking means to permit the operation of said king lever.

55. 7. In a railway traffic controlling system, impulse signaling apparatus for communicating between a central point of control and a field station, a plurality of railway traffic governing devices and a change-over relay at said station, a plurality of control levers at said station for controlling said devices locally said devices being subject to control in accordance with the positions of said levers only when said change-over relay is in a reversed position, means for controlling said devices in accordance with the character of different impulse signals transmitted from said central point effective only when said change-over relay is in a normal position, a locally operable king lever at said station, means effective only when said king lever is in its reversed position for operating said change-over relay from normal to reverse in response to a special impulse signal transmitted from said central point, means for transmitting a distinctive impulse signal to said central point

when the change-over relay assumes its reversed position, means for transmitting a different impulse signal to said central point in response to the subsequent operation of said king lever to its normal position, and means for locking said change-over relay in its reversed position when said king lever is in its normal position.

8. In a railway traffic controlling system, impulse signaling apparatus for communicating between a central point of control and a field station, a plurality of railway traffic governing devices and a change-over relay at said station, a plurality of control levers at said station for controlling said devices locally said devices being subject to control in accordance with the positions of said levers only when said change-over relay is in a reversed position, means for controlling said devices in accordance with the character of different impulse signals transmitted from said central point effective only when said change-over relay is in a normal position, a locally operable king lever at said station, means effective only when said king lever is in its reversed position for operating said change-over relay to reverse or to normal in response to special signals transmitted from said central point, means for transmitting distinctive impulse signals to said central point to indicate the position assumed by said change-over relay, means for locking said king lever in its reversed position when said change-over relay is in its normal position, and means adjacent said king lever controlled by said change-over relay to indicate when said locking is released.

9. In a railway traffic controlling system, impulse signaling apparatus for communicating between a central point of control and a field station, a plurality of railway traffic governing devices and a change-over relay at said station, a plurality of control levers at said station for controlling said devices locally said devices being subject to control in accordance with the positions of said levers only when said change-over relay is in a reversed position, means for controlling said devices in accordance with the character of different impulse signals transmitted from said central point effective only when said change-over relay is in a normal position, a locally operable king lever at said station, means for transmitting a distinctive impulse signal to said central point in response to the operation of said king lever from normal to reverse when said change-over lever is in its reversed position, means effective only when said king lever is in its reversed position for operating said change-over relay from reverse to normal in response to a special impulse signal transmitted from said central point, and means for transmitting a different impulse signal to said central point in response to the operation of the change-over relay to its normal position.

10. In a centralized traffic control system for railroads, a communication system connecting a central point of control and a field station, a track switch at said station, signals for governing traffic movements over said switch, means including said communication system for controlling said switch and signals from said central point, switch and signal levers at said station for locally controlling said switch and signals, change-over relay means at said station which in one position renders said switch and signals subject to control from said central point and in another position renders said switch and signals subject to control by said levers, and means including

said communication system for controlling the position of said change-over relay means from said central point.

11. In a centralized traffic control system for railroads, a communication system connecting a central point of control and a field station, a track switch at said station, signals for governing traffic movements over said switch, a dual system of control for said switch and signals comprising means including said communication system for controlling the operation of said switch and signals from said central point, switch and signal levers for controlling such operation of said switch and signals from a second point of control, change-over relay means which in one position renders said switch and signals subject to control from said central point and in another position renders said switch and signals subject to control by said levers, means including said communication system for controlling the position of said change-over relay means from said central point, and means controllable locally at said second point of control for at times preventing a change in the position of said change-over relay means.

12. In a centralized traffic control system for railroads, a communication system connecting a central point of control and a field station, a track switch at said station, signals for governing traffic movements over said switch, means including said communication system for controlling the operation of said switch and signals from said central point, switch and signal levers for locally controlling such operation of said switch and signals, change-over relay means which in one position renders said switch and signals subject to control from said central point and in another position renders said switch and signals subject to control by said levers, means including said communication system for controlling the position of said change-over relay means from said central point, and means for preventing a change in the position of said change-over relay means except when said switch and signals are in their normal positions.

13. In a centralized traffic control system for railroads, a code type communication system connecting a central point of control and a field station, a track section at said station, main signals and shunting signals for governing traffic movements over said section, code responsive relays controlled through the medium of said communication system for controlling the operation of said main signals from said central point, a signal lever for locally controlling the operation of said shunting signals, change-over relay means which in one position renders the operation of said main signals subject to control by said code responsive relays and in another position renders the operation of said shunting signals subject to control by said lever, and other code responsive relays controlled through the medium of said communication system for controlling the position of said change-over relay means from said central point.

14. In a centralized traffic control system for railroads, a communication system connecting a central point of control and a field station, a track switch at said station, means including said communication system for controlling the operation of said track switch from the central point, a switch lever for controlling such operation of the track switch, change-over relay means which in one position renders said switch subject to control from said central point and in another posi-

tion renders said switch subject to control in accordance with the position of said switch lever, and means including said communication system for controlling the position of said change-over relay means from said central point.

15. In a centralized traffic control system for railroads, a communication system connecting a central point of control and a field station, a track switch at said station, means including said communication system for controlling the operation of said track switch from the central point, a switch lever for controlling such operation of the

5 track switch, change-over relay means which in one position renders said switch subject to control from said central point and in another position renders said switch subject to control in accordance with the position of said switch lever, and means effective only when the track switch and its control lever are both in their normal positions for controlling the position of said change-over relay means from said central point.
